UNITED STATES PATENT OFFICE

156,337

FISHING REEL

George E. Hammer, Chicago, Ill.

Application June 6, 1947, Serial No. 139,496

Term of patent 14 years

(Cl. D31—4)

To all whom it may concern:

Be it known that I, George E. Hammer, a citizen of the United States of America, residing at Chicago, in the county of Cook and State of Illinois, have invented a new, original, and ornamental Design for a Fishing Reel, of which the following is a specification, reference being made to the accompanying drawing, forming a part thereof.

Fig. 1 is an end view of a fishing reel showing my new design;

Fig. 2 is a perspective view thereof showing the front and another end;

Fig. 3 is a similar view illustrating the back of said reel and the end shown in Fig. 1; and

Fig. 4 is a top plan view thereof.

I claim:

The ornamental design for a fishing reel, as shown.

GEORGE E. HAMMER.
